UNITED STATES PATENT OFFICE.

VERNON R. DONCASTER, OF ORLEANS, VERMONT.

BOTTLE-CAP.

1,231,508.

Specification of Letters Patent. Patented June 26, 1917.

Application filed November 16, 1916. Serial No. 131,636.

To all whom it may concern:

Be it known that I, VERNON R. DONCASTER, a citizen of the United States, residing at Orleans, in the county of Orleans, State of Vermont, have invented a new and useful Bottle-Cap; and I do hereby declare the following to be a full, clear, and exact description of the invention, such as will enable others skilled in the art to which it appertains to make and use the same.

The present invention relates to a bottle cap, and has for its object to provide a device of this character which embodies novel clamping means for retaining the cap in operative position on the mouth of the bottle, said clamping means being controlled by a finger lever and being detachable from both the cap and the bottle.

Further objects of the invention are to provide a bottle cap by means of which the mouth of the bottle may be tightly sealed, which can be easily removed without any special form of opener, which can be used repeatedly, and which is of a substantial construction, so that it can be preserved and returned by merchants with the bottle.

With these and other objects in view, the invention consists in certain novel combinations and arrangements of the parts as will more fully appear as the description proceeds, the novel features thereof being pointed out in the appended claim.

For a full understanding of the invention reference is to be had to the following description and accompanying drawings, in which:—

Figure 1 is a side elevation of the neck of a bottle provided with a cap constructed in accordance with the invention, the clamping bail and finger lever being shown by full lines in operative position, and by dotted lines in inoperative position.

Fig. 2 is a similar view, looking at the bottle neck from a position at right-angles to that of Fig. 1.

Fig. 3 is a sectional view through the finger lever.

Fig. 4 is a side elevation of the bottle neck and cap, looking at the same from the side opposite to that shown by Fig. 2.

Fig. 5 is a top plan view of the bottle neck and cap.

Corresponding and like parts are referred to in the following description and indicated

in all the views of the drawings by means of reference characters.

Referring to the drawings, which illustrate one embodiment of the invention, the numeral 1 designates a bottle neck which is of the conventional construction, the mouth thereof being adapted to be closed by a flanged cap 2. The interior of this cap may be provided with the usual disk or lining arranged to engage and tightly seal the mouth of the bottle when the cap is forcibly pressed in position thereon.

A downwardly facing hooked lug 3 projects laterally from one side of the bottle neck at a point slightly spaced from the top thereof, while a larger lug 4 projects laterally from the opposite side of the bottle neck, said lug being provided with a downwardly facing cam shoulder 4^a. These two lugs 3 and 4 are preferably molded integral with the bottle, although it will be understood that they can be provided thereon in any suitable manner.

A clamping bail B extends transversely across the top of the cap 2, being preferably formed of a pair of crossed wires 5. At one end of the clamping bail the crossed wires 5 terminate in a downwardly extending loop 6 which engages the hooked lug 3. At the opposite end of the clamping bail the extremities of the wires 5 are carried downwardly, as indicated at 7, and coiled around the ends of a transversely extending pivot pin 8. The wire coils are shown at 7^a, while the pivot pin is shown as provided at its ends with the heads 8^a, so that the pin is held securely against longitudinal displacement. This pivot pin 8 engages the intermediate portion of a finger lever C, said finger lever including an upper arm 9 and a lower arm 10, which are disposed in a slight angular relation to each other. The pivot pin 8 engages the finger lever at the intersection of the two arms 9 and 10, and the arm 10 is provided at its lower end with an outwardly deflected finger piece 11.

As indicated by Fig. 3, the finger lever C is preferably formed by longitudinally doubling a thickness of material upon itself, the inner thickness 12 having the lower end thereof bent around the outer thickness 13, as indicated at 14, and being crimped at 15 to provide a bearing for the pivot pin 8. This crimped portion 15 is at the inter-

section of the two arms 9 and 10 and bears against the side of the bottle to provide a fulcrum for the lever when the nose 9^a at the extremity of the arm 10 is in engagement with the cam face 4^a of the lug 4.

When the finger lever C is in operative-position, as indicated by Fig. 1, the arm 10 thereof fits substantially against the side of the bottle neck, so as to be in alinement with the arms 7 of the clamping bail B, while the nose 9^a of the arm 9 is inclined outwardly and in engagement with the cam face 4^a of the lug 4. In swinging the finger lever into operative position, the arm 9 thereof is swung outwardly, so that nose 9^a coöperates with the cam face 4^a of the lug to draw the clamping bail B downwardly and force the bottle cap into a tight engagement with the mouth of the bottle neck. It will also be noticed that when the finger lever is in operative position, the arm 9 thereof is swung beyond a dead center relation to the arms 7 of the clamping bail, so that the tension in the arms of the clamping bail serves to lock the lever in position.

In order to remove the cap, the finger piece 11 is engaged by the fingers and the whole arm 10 of the lever swung outwardly away from the bottle neck. This swings the upper arm 9 inwardly toward the bottle neck and finally carries the pivot pin 8 outwardly and upwardly, so as to release the bail, as indicated by dotted lines on Fig. 1, and admit of both the bail and cap being bodily removed. The finger lever itself preferably has a resilient formation, so that any excessive strains will be taken up without danger of breaking the lugs or pulling the clamping bail out of shape. The clamping bail itself can be easily formed from a single

length of wire, and the entire closure can be used repeatedly. In fact, merchants can save and return the closures in the same manner in which they now save and return empty bottles.

Having thus described the invention, what I claim as new and desire to secure by Letters Patent, is:—

In a device of the character described, the combination with a bottle neck having a pair of lugs projecting from opposite sides thereof, one of said lugs being formed with a downwardly facing cam shoulder, of a removable cap fitted upon the bottle mouth, a clamping bail extending across the top of the cap and having one end thereof looped for engagement with one of the lugs, a transverse pivot pin carried by the opposite end of the bail, and a locking lever formed with a long arm and a short arm having an angular relation to each other, said finger lever being built up of two superposed thicknesses of sheet material and one of said thicknesses being crimped at the intersection of the arms to provide a bearing for the tubular pin and a fulcrum for engagement with the bottle neck, the short arm of the lever being adapted to be forced outwardly under the before mentioned cam shoulder of one of the lugs for coöperation therewith to draw the cap tightly against the mouth of the bottle when the long arm of the lever is being swung against the bottle neck.

In testimony whereof I have signed my name to this specification in the presence of two subscribing witnesses.

VERNON R. DONCASTER.
